UNITED STATES PATENT OFFICE

ALBERT F. FIFIELD, OF NEWARK, NEW JERSEY, ASSIGNOR TO THE SINGER MANUFACTURING COMPANY, OF ELIZABETH, NEW JERSEY, A CORPORATION OF NEW JERSEY

THREAD-CUTTING MECHANISM FOR SEWING MACHINES

Application filed December 20, 1930. Serial No. 503,699.

This invention relates to sewing machines, more particularly of the lock-stitch cylinder-bed type adapted for the sewing on of shank buttons, and has for an object to provide a simplified mechanism for severing both the needle and bobbin-threads of such a machine. Another object of the invention is to simplify the thread-cutting mechanism disclosed in the patent to Barron et al., No. 1,336,808, of April 13, 1920.

To the attainment of the ends in view the invention comprises the devices, combinations and arrangements of parts hereinafter described and claimed.

The features of the invention and the advantages attained thereby will be readily understood by those skilled in the art from the following detailed description of a specific embodiment of the invention illustrated in the accompanying drawings, in which Fig. 1 is a front side elevation of a shank-button sewing machine embodying the invention. Fig. 2 is a reverse side elevation of the machine. Fig. 3 is a rear end elevation of the machine. Fig. 4 is a front end elevation of the work-holding and stitch-forming devices. Fig. 5 is a plan view of the free end of the work-supporting arm of the machine with the throat-plate removed to show the thread-cutting devices. Fig. 6 is a similar view with the thread-cutting devices in thread-cutting position. Figs. 7, 8 and 9 are a series of views showing successive stages in the handling of the last needle-loop prior to the actual severing of the needle and bobbin-threads. Fig. 10 is a perspective view of the under side of the throat-plate. Figs. 11 and 12 are vertical sections through the sewing point, taken longitudinally of the work-supporting arm and showing the thread-cutting devices in their initial and in their final positions. Fig. 13 is an enlarged vertical sectional view taken on the line 13—13, Fig. 6. Fig. 14 is a section through the fulcrum of the automatically actuated lever for the needle-loop severing im-

plement, shown in Fig. 1. Figs. 15 and 16 are perspective views of the stop-motion control mechanism of the machine. Fig. 17 is a view of a portion of the mechanism shown in Fig. 1 at a different time in the cycle of operations, and Fig. 18 is a section on the line 18—18, Fig. 6.

Except for certain modifications herein-after pointed out, the machine illustrated is constructed substantially in accordance with the disclosure of the Barron et al. patent referred to. The frame of the machine comprises the standard 1, cylinder-bed 2, and overhanging bracket-arm 3 terminating in the head 4 in which is mounted the laterally vibrating needle-bar 5 and spring-pressed presser-bar 6 carrying, respectively, the needle 7 and presser-foot 8. The presser-bar 6 also carries the usual button-clamp 9 having the separable jaws 10 which grip the shank 11 of the button 12 and hold it in stitch-receiving position upon the fabric 13 held by the presser-foot 8 upon the throat-plate 14, which parts 8 and 14 constitute a cloth-clamp or work-holder. The pressure-bar has fixed thereto the usual lifter-block 15 under the shoulder 16 of which extends the end 17 of the manually operated presser-bar lifting lever 18 fulcrumed at 19 and constituting, in this instance, manually operated mechanism for opening the work-holder for the insertion and removal of work. In practice, there is secured to the lever 18 by screws 20 and arm 21 the rearwardly disposed free end of which is connected to a suitable treadle or knee-shift, not shown.

The needle 7 cooperates with the usual oscillatory shuttle 21, including the thread-case 22 carrying the bobbin 23, Fig. 4, to form stitches; the needle and shuttle being actuated by the usual connections with the main-shaft 24. The main-shaft also drives the cross-shaft 25 to which is fixed the stop-motion controlling cam 26 and the needle-bar vibrating cam 27. The shaft 25 is driven at a

slow speed and ordinarily makes one revolution for each button-sewing cycle. In the present instance, however, controlling means are provided whereby the shaft 25 may, at the will of the operator, be caused to make two revolutions before the machine is automatically brought to rest, thus doubling the number of button-attaching stitches.

The main-shaft 24 carries at its rearward end the tight and loose belt-pulleys, 28 and 29, respectively, and the stop-cam 30 with which cooperates the usual upwardly spring-pressed plunger 31 carried by the tilting stop-motion lever 32. The stop-motion lever 32 carries the usual belt-shipper 33 and includes the forwardly extending arm 34 which is connected by the pull-rod 35 to a suitable starting treadle or knee-shift (not shown). The arm 34 of the stop-motion lever 32 carries a roller-stud 36 which is embraced by the forked arm 37 of a bell-crank lever the other arm 38 of which carries a roller-stud 39 resting in the notch 40 in the cam 26 when the machine is at rest.

When the stop-motion lever 32 is tilted to running position, Fig. 15, by a down-pull on the starting rod 35, it is retained in such position by engagement of the hooked end 41 of the spring-pressed latch-arm 42 with the arm 43 which is rigidly mounted upon and constitutes a part of the stop-motion lever 32. By this movement of the stop-motion lever 32, the roller 39 is moved outwardly from the notch 40 in the stop-motion controlling disk or cam 26. There is mounted on the cam 26 a tripping-plate 44 having an inclined nose 45 adapted to strike the tail-pin 46 of the latch-lever 42 and deflect such tail-pin inwardly, thereby withdrawing the hooked end 41 of the latch-lever from the arm 43 and releasing the stop-motion lever 32 for movement to stopping position under the influence of its spring 47, Fig. 2. The tripping-plate 44 is so timed upon the cam 26 that when its nose 45 engages the tail-pin 46 to release the stop-motion lever 32, the trailing end of the notch 40 has just passed the roller 39 and is in the position shown in Fig. 16. Thus, although the stop-motion lever 32 has been released from the hold of the latch-lever 42, it cannot move to stopping position but is retained in running position by the roller 39 riding upon the circular portion of the periphery of the cam 26. If, therefore, the operator pulls down on the rod 35 to start the machine and holds the rod down until the tripping-nose 45 passes the tail-pin 46, the latch-lever 42, in its recovery, will re-engage the stop-motion lever 32 and hold it in running position for one revolution of the cam 26. At the end of the first revolution of the cam 26, the latch-arm 42 will be tripped by the tripping nose 45 and the roller 39 will be permitted to ride upon the circular portion of the periphery of the cam

26 to retain the stop-motion lever 32 in running position during the second revolution of the cam 26 at the end of which the roller 39 will drop into the notch 40 and permit the stop-motion lever 32 to return to stopping position, (shown in full lines in Fig. 2). The tripping-plate 44 is secured to the cam disk 26 by means of two screws 48, 49. The screw 48 passes through a slot 50 in the tripping-plate 44 to permit adjustment of the tripping-plate 44 about the screw 49 as a center. Inasmuch as the screw 49 is located close to the axis of the shaft 25, the adjustment provides for the accurate timing of the tripping-nose 45 upon the cam 26.

The bobbin-thread pull-off and severing device, per se, is constructed substantially in accordance with the disclosure of the Barron et al., patent referred to. It comprises a reciprocatory bar 51 mounted on top of the work-supporting arm 2 and carrying at its forward end the vertically spaced cutter and pull-off blades 52 and 53, respectively. A stationary blade 54 is mounted on the under side of the throat-plate 14 in the path of the space between the blades 52 and 53. When the bar 51 carrying the blades 52 and 53 is projected from its inoperative position, Fig. 11, to its operative position, Fig. 12, the pull-off blade 53 engages the bobbin-thread 7 and passes under the stationary blade 54, thereby forming a bight in the bobbin-thread and pulling a length thereof from the bobbin 23. The cutter-blade 52 passes over the stationary blade 54 and, being considerably shorter than the pull-off blade 53 does not engage and sever the bobbin-thread until after the pull-off movement is practically completed. The bar 51 is connected by the link 55 to the bell-crank lever 56 which latter is connected by the link 57 to the rearward end of the lever 18 lying behind the stop-motion controlling cam 26. The bobbin-thread pull-off and severing device is thus connected to the work-clamp opening mechanism and is manually operated by the same means which opens the work-clamp.

An interlocking device is provided to prevent the opening of the work-clamp while the stop-motion lever 32 is in running position and to prevent the shifting of the stop-motion lever to running position while the work-clamp is open. This device comprises a link 58, Fig. 2, fulcrumed at its upper end at 59 on the sewing machine frame and connected at its lower end by means of a link 60 to a downwardly extending arm 61 rigidly mounted on the stop-motion lever 32. When the stop-motion lever is shifted to running or dotted line position, Fig. 2, the link 58 is engaged by a roller-stud 62 on the bell-crank lever 56 and blocks the motion of the bell-crank lever 56 and all parts connected to it, including the manually operated work-holder opening or presser-lifting lever 18 and its extension 21.

Also, it is obvious that when the work-holder is manually opened, the roller stud 62 on the bell-crank lever 56 will be moved to the right to a position close to the full line position of the link 58 and will thus block the movement of the stop-motion lever 32 to its running position while the work-holder is open.

The needle-loop detaining and severing device comprises a pair of superposed pointed blades 63, 64 secured by the screw 65 to the lever 66 which is fulcrumed on the stud 67 of the bracket-piece 68 screwed to the under side of the table plate 69 on which the throat-plate 14 is mounted. The table-plate 69 has a shank 70, Figs. 1 and 18, by which it is secured to the work-supporting arm 2 of the sewing machine frame. The underlapping-blade 64 is the loop-detaining blade and its function is to enter the last needle-loop being drawn out by the shuttle 21, as shown in Fig. 7, following which such loop is drawn up by take-up to a position snugly embracing the loop-detaining blade 64 and the bobbin-thread *b*, as shown in Fig. 8. The overlapping-blade 63 is provided with a curved thread-deflecting edge 71 leading to a cutting-edge 72. The function of the blade 63 is to deflect or guide the work-limb of the needle-loop to the cutting edge 72 which, in the final movement of the blades 63 and 64, severs the work-limb of such loop in cooperation with the sharpened extremity of the ledger-blade 73; such ledger-blade being mounted on the under side of the throat-plate 14, as shown in Figs. 10 and 13.

The lever 66 with its blades 63 and 64 is designed to operate with a two-stage movement, the first stage of which is automatically imparted to the lever 66 and the second stage of which is derived from a manual operation after the machine comes to rest. The first or automatic stage of movement of the lever 66 is derived from the trailing inclined end 74 of a cam-plate 75 mounted on the cam 27. The cam-plate 75 cooperates with the roller-stud 76 on the upper end of the lever 77 fulcrumed at 78 to the sewing machine frame. The lever 77 is connected at its lower end by means of a ball-and-socket joint 79 to one end of a yieldingly compressible link 80 the other end of which is connected by the ball-and-socket joint 81 to the lever 66. The link 80 includes the tubular member 82 which houses the compression spring 83 and is entered by the plunger 84 having a shoulder 85 which bears against the spring 83. The plunger 84 carries a cross-pin 86 working in guide-slots 87 in the tubular member 82. A spring 88 coiled about the fulcrum-screw 78 bears at one end against a screw-pin 89 on the lever 77 and yieldingly urges such lever in a direction to carry the roller-stud 76 toward the cam-disk 27. The other end of the spring 88 is anchored to a stud-pin 90 fixed to the sewing machine frame. The stop-motion

lever 32 is connected to the lever 77 by means of a link 91 which is adjustable in length, as indicated at 92, and is formed at one end with a slot 93 entered by a screw 94 threaded into the lever 77.

The operation is as follows:— When the stop-motion lever 32 is tilted to dotted line or running position, Fig. 1, the link 91 pushes the lever 77 to dotted line position and thereby moves the needle-loop detaining and severing blades 63, 64 from full to dotted line positions, Fig. 5. This movement of the lever 77 shifts the roller 76 slightly out of range of the cam-plate 75, so that said roller 76 will not be acted upon by the cam plate 75 when the latter passes under the roller 76 at the end of the first or second revolution of the cam 27.

When the stop-motion lever 32 is finally released by the movement of the roller 39 into the notch 40 in the cam 26, the cam-plate 75 is under the roller 76, as shown in Fig. 17, and prevents the lever 77 from moving out of its dotted line position, Fig. 1, under the influence of the spring 88. Hence the needle-loop detaining and severing blades 63, 64 remain in their dotted line positions, Fig. 5, when the stop-motion lever 32 is released and moves to its vertical or stopping position, Fig. 1. During the last revolution of the main-shaft 24 and while the stop-cam 30 is depressing the plunger-bar 31 preparatory to the final ascent of the plunger-bar 31 into the stop-notch in the cam 30, the trailing inclined end 74 of the cam plate 75 passes beyond the roller 76 and allows the lever 77 to be moved by the spring 88 from dotted line position, Fig. 1, to full line position, whereby the needle-loop detaining and severing blades 63, 64 are moved from their retracted or dotted line positions, Fig. 5, to their full line positions in the same figure; such movement being the automatically effected first stage movement of the needle-loop detaining and severing blades. During such movement, the needle loop detaining blade 64 enters the last needle-loop being drawn out by the shuttle, as shown in Fig. 7, and detains such loop, as shown in Fig. 8, when the machine comes to rest.

When the operator exerts a down-pull on the lever-arm 21 to raise the bar 6 and presser-foot 8 or, in other words, manually opens the work-holder for removal of the work, the bobbin-thread cutter-bar 51 is manually projected toward the free end of the work-supporting arm 2, as previously explained. During this movement of the bar 51, the block 95 strikes the lever 66 and moves the latter from the full line position shown in Fig. 5, to the position shown in Fig. 6, thereby causing the work-limb of the detained needle loop to be deflected by the curved edge 71 of the blade 63 to the cutting edge 72 which cooperates with the ledger-

blade 73 to sever such work-limb substantially simultaneously with the severing of the bobbin-thread by the cutting edge 52. This last described movement of the blades 63, 64 which is caused by the impact of the block 95 upon the lever 66, is the manually effected second stage movement of the needle-loop detaining and severing device. This movement is permitted by the compression of the 10 spring 83 within the tube 82 of the compressible link 80. When the operator releases the arm 21 to lower the presser-member 8, the blades 63 and 64 are immediately restored to their full line positions, Fig. 5, by 15 the recovery of the spring 83 within the tube 82.

By virtue of the present improvement, provision is made for the severing of both the 20 needle- and bobbin-threads, without encumbering the presser-member of the work-holder and the superstructure of the machine with the various small parts of a thread-cutting mechanism such as shown in the Barron et al. patent previously referred to. The mechanism 25 is simple and is readily applied to a machine of the type shown in said Barron et al. patent.

The second cam-plate 45' on the cam-disk 27 is in the nature of a safety device to prevent 30 actuation of the blades 63, 64 in the early stage of a stitching cycle, in case the stop-motion lever 32 is, for any reason, not properly retained in running position when the inclined cam nose 45 passes the tail-pin 46.

35 Having thus set forth the nature of the invention, what I claim herein is:—

1. A sewing machine having, a reciprocating needle, a bobbin, a throat-plate, a stop-motion mechanism, a needle-loop detaining 40 and severing implement pivotally mounted below said throat-plate, automatic means timed to impart a first stage of movement to said implement about its pivot to cause the latter to enter and detain the last needle- 45 loop, a manually operated bobbin-thread pull-off and severing device, and an operative connection between said manually operated bobbin-thread pull-off and severing device and said needle-loop detaining and severing im- 50 plement, whereby the manual operation of said device imparts a further movement to said implement about its pivot to sever the detained needle-loop.

2. A sewing machine having, a reciprocating 55 needle, a bobbin, a throat-plate, stop-motion mechanism including a control lever shiftable between running and stopping positions, a needle-loop detaining and severing device below said throat-plate, automatic 60 means timed to impart a first stage of movement to said device to cause the latter to engage and detain the last needle-loop, manually operated means for imparting a second stage of movement to said device to cause the 65 latter to sever said needle-loop, and means

connected to said stop-motion lever to restore said needle-loop detaining and severing device to initial position when said lever is shifted to running position.

3. A sewing machine having, in combination, a reciprocating needle, a bobbin, stop-motion mechanism, a reciprocating bobbin-thread pull-off and severing device, manual means for operating said device, an oscillating needle-loop detaining and severing implement, automatic means for projecting said implement into the last needle-loop to detain the latter, and means on said device for imparting a further movement to said implement to sever the needle-loop concurrently with the severance of the bobbin-thread. 70

4. A sewing machine having a reciprocating needle, a bobbin, a throat-plate, a reciprocating bobbin-thread pull-off and severing implement mounted below said throat-plate, and a pivotally mounted needle-loop detaining and severing implement disposed below 85 said throat-plate and above said bobbin-thread pull-off and severing implement.

5. A sewing machine having, a reciprocating needle, a bobbin, a throat-plate, a reciprocating bobbin-thread pull-off and severing implement mounted below said throat-plate, and a pivotally mounted needle-loop detaining and severing implement disposed below 90 said throat-plate and above said bobbin-thread pull-off and severing implement, automatic means for imparting a first stage of movement to said needle-loop detaining and severing implement to cause the latter to detain the last needle-loop, and manual means for operating said bobbin-thread pull-off and severing implement and for imparting a second stage of movement to said needle-loop detaining and severing implement to cause 95 the latter to sever the detained needle-loop. 100

6. In a sewing machine, a reciprocating needle, a loop-taker, a bobbin, a throat-plate, a pivotally mounted needle-loop detainer and cutter, a bobbin-thread cutter, both of said cutters being mounted below said throat-plate for movement independently of one-another, automatic means for pivotally moving said needle-loop cutter to detain the last needle-thread loop, and manual means for moving 110 said bobbin-thread cutter to sever the bobbin-thread and for further pivotally moving said needle-loop cutter to sever the detained needle-loop. 115

7. In a lock-stitch cylinder-bed sewing 120 machine, the combination with the frame including the cylinder-bed and overhanging arm, of stitch-forming mechanism incorporated in said frame and including a reciprocating needle and complementary loop-taking 125 means, a stop-motion device, a bobbin-thread pull-off and severing device including a manually operated slide-bar mounted for endwise reciprocatory movements lengthwise of said cylinder-bed, a needle-loop detaining and sev- 130

ering device pivotally mounted at the free end of said cylinder-bed, and automatic means for imparting a first stage of pivotal movement to said needle-loop detaining and severing device to cause it to enter and detain the last needle-loop, said slide-bar being adapted to engage and impart a further pivotal movement to said needle-loop detaining and severing device to cause the latter to sever the detainted needle-loop when the bobbin-thread is severed.

In testimony whereof I have signed my name to this specification.

ALEBERT F. FIFIELD.
